Benjamin Griff

Letters Patent.

Issued May 25, 1806.

The schedule referred to in this Letter Patent and making part of the same containing a description in the words of the said Benjamin Griff himself of his machine for shearing cloth.

This shearing machine is constructed in the following manner. First it consists of a frame, which supports the whole machinery, of about four feet and three inches in height, three feet seven inches in width and three feet three inches in height. At the top of the front plates are framed into them so high as to be even with the top of the main posts of the frame, about six inches from one end of the former, are placed two short posts framed into the side plates opposite each other of about seven inches in height, on these short posts rests a shaft which turns and carries first, a balance wheel of thirty inches diameter, and a egg wheel of fourteen and a half inches diameter and seventy-five egg placed ten inches distant from the balance wheel. This egg wheel operates upon a pinion made to revolve it of two inches and three fourths diameter and twelve eggs. This pinion is connected with, or attached to a shaft which is supported by two short studs framed into the end plates at the distance of about six inches from each end of said plates. On each end of this last mentioned shaft, is a crank of one and a quarter inch. To each of these cranks is attached a rod which is connected with a sliding frame. This frame is constructed to move in a horizontal direction by the operation of the cranks in turning. This sliding frame carries the shear. Immediately under this former is another

1934 of the same length, that is to say, about two feet to which is attached the under shear. The sliding frame being made to move on the frame of the under shear these frames with which the shear are connected are attached to the side plates of each of the rods which connect the sliding frame with the counter is attached a rod in a perpendicular position and the upper ends of these perpendicular rods are connected with the ends of two levers, which pass through a roller nearly over the shear, and are continued as far as the ends of the sliding frame. These levers are connected at the ends immediately above the ends of the sliding frame, by two hooks placed in a perpendicular position with the ends of the frame in which the under shear is placed. The slant which supports the roller are joined with the side plates of the frame and are about fourteen inches in height. The above mentioned levers being operated upon by means of the crank with which they are connected as above described, and running upon the roller above mentioned causes the shear frames to rise and fall in the operation of shearing. The under shear is placed at right angles with the side plates and the upper shear a little obliquely, so that when they close at the heel they will be open at the other end about two inches and a half - on the opposite end of the shaft of the balance wheel and cog wheel above mentioned is a pinion of one inch and a $\frac{1}{16}$ with eight cogs. This pinion matches a cog wheel of twenty seven inches diameter and one hundred and forty four cogs which last mentioned is on a short shaft passing through the side plate near the end, on the other end of this short shaft is a pinion of two inches diameter and eight cogs; this pinion being on the inside and the last mentioned wheel on the outside of the frame plate and close to it on each side this last pinion is to operate upon a cog wheel of thirty inches in diameter and one hundred and twelve cogs which is fastened by ~~means of~~ ^{means of} a pin on the end

of a cylinder of the same size. This cylinder is calculated to turn by means of the pinion and cogwheels mounted in the same way that the lathe wheel or work wheel has turned one hundred and fifty two times. This cylinder in turning receives the cloth after it has passed under the shear in the process of shearing. The cloth is drawn off a shear board of about six inches deep, and one inch and a half thick and is mounted on the upper side when the cloth rests upon it for the shear to strike it so they are made to rise and fall by means of the board above described. This shear board is placed under the shear in such manner that the shear strikes near the centre of the upper edge of it in the operation of shearing and is fitted in grooves made in the side plates of the frame, and is at right angles with them. This shear board is continued by means of screws to be raised or lowered as occasion may require. In the process of shearing the cloth is drawn off a small, ^{the bottom of} a cylinder fixed in the end of the frame opposite the large cylinder before mentioned nine inches below the plate at the top of the post at the same end. This small cylinder is governed by a short lever and an iron rod bent to the cylinder near the end and by a small weight acting upon this lever. The function is intended to so to prevent the cloth from running off too fast. In shearing, the large cylinder is made to fall from its place when the last end of the cloth passes under the shear so that the cogwheels are not operated upon by this pinion intended to turn the large cylinder. This is effected by means of a lever placed under the pinion of the cylinder at one end and the other resting on a book is caused to fall by a rod attached to the cloth on the small cylinder. It is also designed to construct a brush to turn upon the cloth for the purpose of raising the nap thereof directly before the shear. This brush is to be in the form of a cylinder and will turn on a shaft passing through the side plates.

6934
The operation of this brush is to be performed by means of a strap passing round a pulley upon the end of this shaft and connected with another pulley on the end of the shaft, upon which is the wheel above mentioned on the outside of the frame. The above described machine is constructed so as to be worked either by water or by hand, if by water it may be done by means of a strap passing round the balance wheel and communicating with the water wheel so the business of shearing may be performed by hand with great ease by fixing a counter on the end of the shaft of the balance wheel on the same end with said wheel on
